UNITED STATES PATENT OFFICE.

JOHN E. COSTELLO, OF PROVIDENCE, RHODE ISLAND.

LETTER-BOX.

SPECIFICATION forming part of Letters Patent No. 613,795, dated November 8, 1898.

Application filed August 18, 1898. Serial No. 688,902. (No model.)

To all whom it may concern:

Be it known that I, JOHN E. COSTELLO, of Providence, in the county of Providence and State of Rhode Island, have invented certain new and useful Improvements in Letter-Boxes; and I do hereby declare that the following is a full, clear, and exact description thereof, reference being had to the accompanying drawings, and to the letters of reference marked thereon, which form a part of this specification.

This invention relates to the class of letter-boxes used in cities to receive letters and papers in various locations for collection and transmission to the post-office. It is fully explained and illustrated in this specification and the accompanying drawings.

Figure 1 shows a perspective view of the letter-box. Fig. 2 is a vertical cross-section taken on line 2 2 in Fig. 1. Fig. 3 represents the upper part of Fig. 2 with the box closed. Fig. 4 is a separate view of the circular slide.

The object of this invention is to furnish a receptacle for letters and papers that will be simple in its construction and operation and therefore not likely to get out of order and that can be opened and the letter or paper deposited in it with one hand. Its construction is as follows:

30 A is a case, preferably made of metal in a rectangular form. The top of this case is covered by a cap B, made in a horizontal semicylindrical shape and secured to the case H by means of screw-rivets that pass through 35 ears o o on the upper edge of the case and the ends of the cap.

A chute to receive the letters is made in the top of the case A, consisting of the two plates d and d', which are attached permanently to the ends of the case inside, or they may be cast integral with the case. This chute is open at its top and bottom and extends above the case A nearly to the top inside the cap B, and the front plate of the case 45 is carried up both at the front and sides to the edge of the plate d', so as to close the space between the edge of the case and the chute.

A circular slide C is made, preferably, of 50 sheet-steel rolled into the cylindrical shape

seen in Fig. 4. This circular slide is fitted to go easily in the top of the cap B and is held up in place by projecting ridges c, made on the inside of each end of the cap, and also by like projecting ridges e e, made on the ends 55 inside of the case A. A portion s of the circular slide C is turned out radially at its upper edge, by which the slide is operated and which when the slide is in place projects out of the open space left in the front of the cap 60 between i i' and which extends the whole width of the case.

When the letter-box is open for the reception of letters, the slide C is moved around in its place so that the handle s is at the top 65 of the opening in the front of the cap, as in Figs. 1 and 2, and the whole space between i and i' and from end to end of the cap is open, affording ample room for putting in letters or 70 papers.

When the slide C is moved to open the letter-box, it slides around under the inner end of the chute on the ridge e, (see Fig. 2,) so as to close the inner end of the chute and prevent communication with the case below, the 75 ridges e preventing any forcing of the lower edge of the slide open, and when the letter-box is closed by pulling the handle s down, as in Fig. 3, the front of the case being carried in a little way on the same circle as the 80 cap to allow sufficient motion for the slide, the inner end of the chute is open for the letters and papers to fall into the case below.

A door J is made in one side of the case A for the purpose of taking the letters and papers out when necessary, and it may be fastened with a lock in the usual way. The construction and location of the door are notes- 85 sential, and it may be placed where it will be most convenient for use.

Having thus described my improvement, I claim as my invention and desire to secure by Letters Patent—

1. In a letter-box the combination of a case to receive the letters, a cap of semicircular 95 shape having an open space in front extending the full width of said cap, a plate cylindrical in shape, open at the ends, and fitted to slide in said cap on curved ridges, substan- tially as described.

2. In a letter-box the combination of a case having a cap, a stationary chute held in said cap and attached to it at both ends, a curved plate fitted to slide on curved ridges made on the inside of said cap, and adapted to close the upper end of said chute and open the lower end when drawn forward, and to close the lower end of said chute, and open the

upper end when pushed back, substantially as described.

In testimony whereof I have hereunto set my hand this 16th day of August, A. D. 1898.

JOHN E. COSTELLO.

In presence of—

BENJ. ARNOLD,

HOWARD E. BARLOW.
